REFRIGERANT BUNKER FOR CONTAINERS

Graham C. Woodruff, Bronxville, N. Y., assignor
to The L. C. L. Corporation, a corporation of
Delaware

Application July 9, 1935, Serial No. 30,497

6 Claims. (Cl. 62—91.5)

In the drawings:

Figure 1 is a vertical sectional view of a refrigerator container embodying my invention.

Figure 2 is a detail vertical sectional view of a refrigerator container showing another embodiment of my invention.

Figure 3 is a sectional view on the line Y—Y, Figure 2.

Figure 4 is a detail vertical sectional view of a refrigerator container showing still another embodiment of my invention.

Figure 5 is a sectional view on the line X—X, Figure 4.

My invention relates to refrigerant bunkers, especially adapted for use in refrigerator containers, of the type designed to be loaded on railroad cars side by side; the object of my invention being to provide a bunker designed to be convertible, whereby such refrigerants as ice, salt or brine ice, or solid carbon dioxide, and the like, may be used in said bunker.

A further object of my invention is to provide the necessary heat absorbing and heat emitting surfaces and heat transmitting capacities without interfering with the usual practices in the construction of refrigerated storage and transportation units; and with these and other objects in view my invention consists of the parts and combination of parts herein pointed out in the claims.

The reference numeral 1 designates a transportation container which, in form and exterior dimensions, corresponds closely to merchandise containers such as are transported on railway cars, trucks, or the like, which are generally arranged side by side or end to end, occupying the full platform space of the vehicle. The container is provided with hooks or links 2 designed to be engaged by a chain from a hoist for the purpose of lifting or shifting the containers from the vehicle to a platform, or vice versa. The containers may be handled by lift trucks.

The walls, roof and floor of the container are to be suitably insulated and a door 3 is provided in one of the walls of the container for the purpose of loading and unloading goods into and from the interior of the container.

The roof of the container is provided with a hatchway 4 which is provided with a hatch cover 5, suitable means being used to seal the joint between the hatchway and its cover 5, said cover being provided with insulation 6.

My convertible bunker comprises a body portion 7, which extends, in the preferred construction, from wall to wall of the container whereby

the bottom wall 8 presents a large conductor surface. The bunker, in the preferred form, is provided with a filling opening or hatchway 9, the upper portion of the walls of which are rebent as at 10 and rests on the top of the container to support the bunker in the container. It is obvious that many expedients may be adopted to support the bunker within the scope of the appended claims.

In the primary scope of my invention I provide 10 a sleeve 11 designed to have a neat sliding fit in the filling opening 9, and is, therefore, adapted to be moved to bring its lower edge into intimate contact with the inner face of the bottom wall 8 of the bunker, thereby converting the bunker to 15 a bunker of restricted area adapted to receive solid carbon dioxide, and in order to control the conductivity of this restricted bunker, I preferably place on the bottom thereof a resistance pad 12. 20

This restricted bunker may be formed in different ways, but for the purposes of this application I have shown the additional adaptations which I will now describe.

In Figure 2 the walls of the filling hatch of 25 the bunker are offset as at 13 to form a recess in which the restricted bunker sleeve 11a is slidably mounted, the sleeve being shown in elevated position in full lines, and in operative position in dotted lines. 30

In Figure 4 the walls of the filling hatch of the bunker are recessed as at 13a. The restricted bunker is formed by members 14 mounted on hinges 15 which are held in inoperative position in said recesses 13a by any suitable means, such 35 as latches 16. Suitable stops 17 are secured in the main bunker to hold the walls of the restricted bunker in proper operative position. In this construction, as in the construction shown in Figure 1, the top portion of the bunker filling 40 hatch is rebent over and rests upon the top edge of said filling hatch, as indicated by the reference numeral 18, and a sheet 19 is arranged around the filling sleeve of the bunker under which is applied suitable insulation 20. 45

The warm air in the goods storage space of the container will rise and on contacting with the outer surface of the bottom wall of the bunker the air will be cooled by such contact and then fall to the bottom of the goods storage space, 50 thereby creating a circulation of air in said goods storage space and efficiently refrigerating the goods in said space.

The restricted bunker sleeve may be bodily inserted in the filling hatch when it is desired to

make the conversion, and the resistance pad 12 inserted within the sleeve to rest on the upper face of the metal bottom of the bunker, said pad to obtain the required temperature regulation 5 within the good storage space.

Means, such as angle shaped retainers 11a, extend around the inside of the hatch opening to hold the sleeve in position. When the sleeve is removed these retainers function as anti-splash 10 flanges, clips, or brackets 11b attached to the bottom wall of the bunker act as guides or retainers for holding the removable sleeves in proper position.

What I claim is:

15. 1. In a refrigerator container a refrigerator unit, comprising a bunker body for the reception of ice, brine and the like, said body having a restricted filling opening, a bunker sleeve adapted to fit and slide in said opening with its lower edge in contact with the bottom of the bunker, thereby providing a bunker of less capacity than the bunker body, whereby said unit may be converted for use of ice, brine or solid carbon dioxide, or a like refrigerant.
20. 2. In a refrigerator container a refrigerator unit, comprising a bunker body for the reception of ice, brine and the like, said body having a restricted filling opening, a bunker sleeve adapted to fit and slide in said opening with its lower edge in contact with the bottom of the bunker, a resistance pad on the bottom of said restricted bunker, thereby providing a bunker of less capacity than the bunker body, whereby said unit may be converted for use of ice, brine or solid carbon dioxide, or a like refrigerant.
25. 3. In a refrigerator container, a casing lined with insulating material, a bunker positioned in the top portion of said casing and having a restricted filling port, offsets forming slideways in the walls of said port, a sleeve slidably positioned in said slideways and adapted to be moved down to contact the bottom wall of the said

bunker, to form a supplemental bunker of less capacity than the main bunker.

4. In a refrigerator container, a casing lined with insulating material, a bunker positioned in the top portion of said casing and having a restricted filling port, offsets forming slideways in the walls of said port, a sleeve slidably positioned in said port and adapted to slide in said slideways to be moved down to contact the bottom wall of the said bunker, to form a supplemental bunker of less capacity than the main bunker, and means to retain the sleeve in its adjusted position. 5

5. In a refrigerated container having a space adapted to contain goods to be refrigerated, and adapted to be cooled by ice, salt ice, or a solid refrigerant, a metallic bunker, at the top of said space and having a refrigerant loading port, means in said port movable to a position in the body of the bunker to form a bunker of restricted 20 cubic capacity as compared with the cubic capacity of the first named bunker, said restricted bunker being adapted to receive a solid refrigerant whereby the metallic bunker may be converted from an ice or salt ice bunker to a solid 23 refrigerant bunker. 13

6. In a refrigerated container having a space adapted to contain goods to be refrigerated, and adapted to be cooled by ice, salt ice, or a solid refrigerant, a metallic bunker, at the top of said 30 space and having a refrigerant loading port, means in said port movable to a position in the body of the bunker to form a bunker of restricted cubic capacity as compared with the cubic capacity of the first named bunker, said restricted 33 bunker being adapted to receive a solid refrigerant whereby the metallic bunker may be converted from an ice or salt ice bunker to a solid refrigerant bunker, and a resistance pad at the bottom of said restricted bunker. 40

GRAHAM C. WOODRUFF.
